(57) **CLAIM**

The ornamental design for a table ornament, as shown and described.

DESCRIPTION

The patent or application file contains at least one drawing executed in color. Copies of this patent or patent application with color drawings will be provided by the Office upon request and payment of the necessary fee.

FIG. 1 is a front, right, and top perspective view of a table ornament, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, left, and top perspective view thereof;

FIG. 9 is a rear, right, and bottom perspective view thereof;

FIG. 10 is a front, left, and bottom perspective view thereof;

FIG. 11 is a front, left, and top perspective view thereof; and,

FIG. 12 is a rear, right, and top perspective view thereof.

1 Claim, 12 Drawing Sheets
